CLAIM

The ornamental design for an LED lighting fixture, as shown and described.

DESCRIPTION

FIG. 1 is a bottom perspective view of a first embodiment of an LED lighting fixture illustrating my new design;

FIG. 2 is a side elevation view thereof;

FIG. 3 is a bottom plan;

FIG. 4 is a side elevation view of a second embodiment of my new invention;

FIG. 5 is a bottom plan view of the second embodiment of my new invention; and,

FIG. 6 is a top plan view of the first and second embodiments of my new invention.
